(57) **CLAIM**

The ornamental design for a “marine propeller with thrust edges”, as shown and described.

DESCRIPTION

FIG. 1 is a left side elevational view of a marine propeller with thrust edges showing my new design;

FIG. 2 is a left side elevational view rotated 90 degrees thereof;

FIG. 3 is an enlarge sectional view along line 3—3 of FIG. 1 thereof;

FIG. 4 is a top plan view thereof; and,

FIG. 5 is a bottom plan view thereof.

The hub of the propeller is shown in broken lines for illustrative purposes only and form no part of the claimed design.
